Fig. 7.

Fig. 8.

FIG. 1 is a side elevational view showing our hoist;
FIG. 2 is a side elevational view of the opposite side
thereof;

FIG. 3 is a rear elevational view thereof;

FIG. 4 is a front elevational view thereof;

FIG. 5 is a side elevational view showing a modifi-
cation of our hoist;

FIG. 6 is a side elevational view of the opposite side
of the hoist shown in FIGURE 5;

FIG. 7 is a front elevational view of the hoist shown
in FIGURE 5; and

FIG. 8 is a rear elevational view of the hoist shown
in FIGURE 5.

This is a continuation of design applications D. 34,309
and D. 34,340, filed Mar. 17, 1965, now abandoned.

We claim:

The ornamental design for a hoist, as shown and de-
scribed.
